UNITED STATES PATENT OFFICE

JAMES FLOCKHART, OF SAN FRANCISCO, CALIFORNIA, ASSIGNOR TO THE FLOCKHART CO., INC., OF SAN FRANCISCO, CALIFORNIA, A CORPORATION OF CALIFORNIA

STENCIL PRINTING APPARATUS

Application filed March 24, 1930. Serial No. 438,504.

This invention relates to improvements in stencil printing apparatus and more particularly to stencil frames therefor.

The principal object of the invention is to provide means for stretching silk cloth stencil screens taut without wrinkling.

Another object is to remove distortion from the stencil in the first and subsequent stretchings.

10 A further object is to provide a frame that is light, compact, rigid, and easily manipulated. Other objects and advantages will appear as the description progresses.

In this specification and the accompanying drawings the invention is disclosed in its preferred form. But it is to be understood that it is not limited to this form because it may be embodied in other forms. It is also to be understood that in and by the claims 20 following the description it is desired to secure the invention in whatsoever form it may be embodied.

In the two sheets of drawings:

Fig. 1 is a fragmentary plan view from above of a stencil frame constructed in accordance with this invention, installed within an adjustable chase or frame.

Fig. 2 is an enlarged detail in vertical section on the line II—II.

30 Fig. 3 is an end view detail taken at the point III, see arrow Fig. 1.

Fig. 4 is a detail view similar to Fig. 1 of a corner of the frame.

35 Fig. 5 is an end elevation of one end of the top rail.

Fig. 6 is a side elevation of the same.

Fig. 7 is an enlarged detail in cross section and perspective of a simplified modification 40 of the stencil frame.

In detail the construction illustrated in the drawings, referring to Fig. 2, comprises a rectangular open rigid integral base frame. The side rails 1, of this frame, have the bottom surface 2, and the inner side 3. The base frame

is preferably integral, but it may be built up of separate parts properly joined.

The outer side 4 and top 5 are milled away to leave the upstanding flange 6, having the rabbit 7, longitudinally under cut therein 50 when the top 5 is milled away.

The top 5 has the grooves 8 and 9 milled therein the length of the side rails 1. The portion of the top and outer side of the rail cut away is replaced by the top rails 10 having the tongue 11 fitting closely within the rabbit 7. These rails are also grooved longitudinally at 12 to aline with the grooves 8 in the bottom rails 1.

The complete frame is composed of the four 60 bottom rails 1 of the base frame, and four top rails 10. At the corners one end of each top rail 10 overlaps the width of the contiguous bottom rail and the end lugs. The cross section of the top rails thus assembled completes 65 the rectangular cross section of the base frame, see Fig. 4. The tongues 11 are cut away at 11', adjacent the corners so that the edges of the top rails can met at 13 at their ends, but leaving the continuation 10' of the 70 under side of the top rail, see Figs. 3, 5.

The top rails are fixed to the base frame by the corner screws 14—14 threaded in the holes 15 in the base frame, see Figs. 1, 3 and 4.

The clamp bars 16 rest within the grooves 75 9 in the base frame in front of the ends of the screws 17 threaded and countersunk in the flanges 6—6.

The screen 18 is applied by laying it on a flat surface and superimposing the base 80 frame with the bottom 2 resting upon the screen. A marginal width of screen equal to the height of the side 4 plus the width of the top 5 and the depth of the groove 9 is allowed and the screen cut to size. The four corners 85 of the screen are then cut away obliquely or "mitered" at the corners. This leaves four side flaps 19 on the area of the screen. These flaps are then folded inward over the tops 5 across the grooves 8 and 9.

The clamp bars 16—16 are then pushed into the grooves 9—9, carrying the edges of the flaps down into the grooves, see Fig. 4. The screws 17—17 are then set up to clamp the edges of the flap in the grooves 9. Some care should be taken in adjusting the screen area 18 to avoid distortion of the warp and woof pattern of the cloth. This can be very easily done by proper manipulation of the flaps 19.

With the clamps 16 set up tight to hold the flaps 19, the flexible rods 20 are laid on top the flaps over the grooves 8. The top rails 10 are then fixed in position on the base frame as described, and held by the screws 14—14 at their opposite ends.

The diameter of these rods 20 extend up into the grooves 12 in their respective top rails 10. The adjusting screws 21—21, are threaded in the rails 10 at intervals and bear against the tops of the rods 20.

When these screws 21—21 are screwed down, they force the rods downward carrying a loop of the flaps 19 down into the grooves 8, to draw the area 18 of the screen taut. In actual practice these rods 20 are about three sixteenths of an inch in diameter and may be distorted by the screws 21 to affect a given area of the screen to remove slack or pull any portion of the stencil pattern into desired registry with the image to be reproduced.

One of the advantages of this invention is that the screen stencils may be removed from the frame after use and filed away flat. If a duplicate order is desired the screens can again be replaced in the frame and the tightening accomplished by the screws 21, and the stencil image restored to its original registry with the master image from which it was made. Heretofore it has been necessary to leave the screen stencil in the frame, tying up capital in inactive frames and storage space. Neither could the stencil image be manipulated to remove puckering or distortions that may occur during storage.

The protection strips 22—22 are added to the outer edges 4 of the frame and held by the screws 23—23 threaded into the top and/or bottom rails 1—1 and 10—10.

Thus assembled, the stencil frame is inserted into the printing frame or chase 24, wherein it is secured by the opposed adjusting screws 25—25. These screws are useful in attaining registry of the screen frame on the platen (not shown), especially in multicolor printing where several stencils are used in producing an image on a surface resting upon the platen. In this connection see my co-pending application entitled Stencil frame, filed September 30, 1929, and bearing Serial Number 396,083.

The structure of the frame, particularly at the corners, has been specifically described, but modifications within the purview of the invention to meet varying requirements, will

be manifest to those skilled in the art, for instance, as shown in Fig. 7.

The modification shown in Fig. 7 consists of two integral rectangular frames 1 α and 10 α . The lower frame 1 α has the channel 8 α 70 in the top thereof to receive the rods 20 α .

The top frame 10 α has a similar channel 12 α for the rods 20 α with the adjusting screws 21 α bearing thereon. The two frames are held together by the marginal screws 14 α at 75 intervals and threaded in the lower frame.

The flaps 19 α of the screen 18 α are carried over the edges of the lower frame, under the rods 20 α and clamped at 16 α between the two frames by the screws 14 α . The slack in the flaps 19 α can be drawn taut before the screws 14 α are set up tight to clamp them.

The flanges 22 α are formed on the top frame 10 α to receive the ends of the adjusting screws 25 in the chase 24, as described in 85 connection with the other form of screen frame. The rod adjustment 20 α and screws 21 α also operate as previously described.

Having thus described this invention, what I claim and desire to secure by Letters Patent is:

1. A stencil frame having grooves therein; flexible rods in said grooves and flexing means on said frame engaging said rods.
2. A stencil frame having stencil clamping means thereon and grooves therein; flexible rods in said grooves and flexing means on said frame engaging said rods.
3. A stencil frame having parallel grooves therein; clamping bars and rods in said grooves respectively; independent adjusting means on said frame engaging said bars and rods respectively.
4. A stencil frame having bottom rails with clamping grooves and adjusting grooves therein; bars in said clamping grooves and rods in said adjusting grooves; independent means on said frame for moving said bars horizontally and said rods vertically.
5. A stencil frame having bottom rails with clamping grooves and adjusting grooves therein; clamping means in said clamping grooves; rods in said adjusting grooves; top rails fixed to said frame and engaging said rods.
6. A stencil frame having bottom rails with clamping grooves and adjusting grooves therein; clamping means in said clamping grooves; rods in said adjusting grooves; top rails fixed to said frame and engaging said rods; and protecting strips attached to said frame.
7. A stencil frame comprising a rectangular base frame with laterally extended bottom rails having adjusting grooves therein and clamping means thereon; flexible rods in said adjusting grooves; top rails fixed to said frame and having adjusting means at intervals engaging said rods; and a screen on said frame having flaps folded over the sides of

said bottom rails, beneath said rods and engaging said clamping means.

8. A stencil frame comprising a rectangular base frame with laterally extended bottom rails having clamping and adjusting grooves therein; bars in said clamping grooves; screws threaded in the side walls of said clamping grooves and engaging said bars; flexible rods in said adjusting grooves; 10 top rails fixed to said frame having screws therein at intervals engaging said rods.

In testimony whereof I have hereunto set my hand this 19th day of March, 1930.

JAMES FLOCKHART.
